(57) **CLAIM**

The ornamental design for a deformed light drone, as shown and described.

DESCRIPTION

FIG. 1 is a top perspective view of a deformed light drone, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a usage state view thereof;

FIG. 10 is a usage state view thereof;

FIG. 11 is a partial enlargement of FIG. 9;

FIG. 12 is a partial enlargement of FIG. 9; and,

FIG. 13 is a partial enlargement of FIG. 9.

The broken lines in the drawings illustrate portions of the deformed light drone that form no part of the claimed design. The dot-dash boundary lines in FIGS. 9, 11, 12, and 13 illustrate the periphery of the enlarged views and form no part of the claimed design.
